GARMENT SUPPORTER

Louis Sametz, Westport, Conn.

Application February 3, 1938, Serial No. 188,403

9 Claims. (Cl. 24—245)

The present invention relates to improvements in garment supporters. More particularly it relates to improvements in the means for attaching the button-supporting tab member to the loop member of such a supporter.

The primary object of the invention is to secure the tab member of a supporter to the loop member in such a manner that it cannot be removed or inadvertently loosened therefrom.

Another object is to secure the tab member to the loop member by means of a novel fastening element which interconnects the loop member with the eye of the garment supporter.

A further object is to secure the fastening element in such a manner to the loop and eye members, and the tab member to the fastening element, that the eye is free to pivot relative to the fastening element while the loop and tab members are substantially rigid with said fastening element and are clamped or gripped by said fastening element.

A still further object of the invention is to provide simple and inexpensive means for strengthening that portion of the tab member which is gripped by the fastening element to prevent ripping or tearing of the tab member, and to provide such strengthening means which do not substantially increase the thickness of the tab member.

Features of the invention include impregnating the end portion of a single-ply member which is secured to the fastening element, and the provision of a metallic fastening element which is provided with teeth for biting into the impregnated end portion of the tab member.

These and other objects, features and advantages of the present invention will appear from the following detailed description and the drawing, in which:

Figure 1 is a front view of the garment supporter in assembled condition.

Fig. 2 is a cross-section taken along the line 2—2 of Fig. 1.

Fig. 3 is a front view of the supporter with the tab member in unlooped position.

Figs. 4 and 5 are fragmentary front and side views, respectively, of the tab member according to the invention.

Fig. 6 is an enlarged fragmentary section showing the tab member in unlooped position.

Fig. 7 is a view similar to Fig. 6 with the tab member in looped position.

Fig. 8 is an enlarged perspective view of the fastening element according to the invention.

Before describing the present improvements

and mode of operation thereof in detail it should be understood that the invention is not limited to the details of construction and arrangement of parts shown in the accompanying drawing, which is merely illustrative of the present preferred embodiments, since the invention is capable of other embodiments, and the phraseology employed is for the purpose of description and not of limitation.

Referring to the drawing in detail, a conventional metallic loop member 8 has a crossbar 9 at its upper end which is secured by means of a fastening element 10 to an eye member 11 of conventional construction.

The fastening element 10 provided by the present invention is particularly novel and highly advantageous. It consists preferably of a flat piece of metal, one end of which is provided with a bent portion 12 which grips tightly around the crossbar 9 of the loop member so as to be substantially rigid therewith or permit only limited movement of the loop member relative to the fastening element 10. Substantially at the middle of its length, the element 10 is passed through the eye member 11 and bent backwardly so as to provide a loop 13 which loosely enfolds and rests on the crossbar 14 of the eye member 11. The other end 15 of the fastening element 10 includes a curved portion 16 which is of sufficient length to curl at least partially around the bent portion 12 and to enter between the side arms 17 of the loop member 8. A single-ply tab member 18 carries a button 19 secured to its lower end and has its upper end portion 20 interposed between the curved portion 16 and the bent portion 12 of the fastening element 10, and this upper end portion 20 is gripped or pressed tightly between the portions 12 and 16.

Preferably, and as shown by the drawing, the end portion 20 of the tab member 18 may extend so far as to terminate between the crossbar 14 of the eye member 11 and the loop 13. However, it may also extend around the crossbar 14, or it may even be of such a length as to be further secured between the bent portion 12 and the crossbar 9 of the loop member.

According to the present invention, to increase the gripping action on the tab member 18, and to prevent pulling out of the tab member from the fastening element 10, the outer edge 21 of the curved portion 16 acts as a biting edge and is provided with teeth or prongs 22. The free end 23 of the tab member is bent upwardly and around the curved portion 16 and looped through the eye member 11, as clearly shown in the draw-

ing. When a pulling force is exerted in downward direction on the button 19 such force is substantially taken up and reduced by the friction of the tab member 18 on the crossbar 14 of the eye member 11 and the curved portion 16, while the residual force is taken up by the edge 21 and the prongs 22 which bite slightly into the surface of the tab member and thus prevent withdrawal thereof from the gripping portions 12 and 16 of the fastening member.

In order to increase the life of the supporter and to prevent tearing of the tab member by the prongs 22, and also to lessen the wear of the tab member by the friction on the metallic fastening element, the upper part 24 of the tab member is preferably provided with strengthening means 25 which may consist for example of an impregnation of the part 24 with cellulose acetate or any other impregnating, coating and/or stiffening material. Such an impregnation produces the advantages that it: binds together the fibers or threads of the tab member, acts as a stiffening and strengthening medium for the part 24 which is most affected by pulling, tearing and frictional forces, and prevents the prongs 22 from biting into the fabric of the tab member 18 and instead causes them to bite into the thin coating on the fabric. The impregnation securely adheres to the fabric without increasing its thickness to any noticeable or undesirable extent.

By means of the new support structure provided by the present invention, the following advantages are obtained: The tab member 18 can under no circumstances come loose of the fastening element 10 either by the normal wear, manipulation or laundering of the supporter; the life of the tab member is considerably prolonged by the coating of cellulose acetate or similar material; the fastening element 10 is of such construction that it cannot interfere with or hook into any garments worn over the supporter since the biting edge 21 is curved inwardly between the side arms 11 of the loop member 8; and, the outer surface of the fastening element 10 is completely covered at both sides thereof by the fabric of the tab member 18 so that no metal parts of said fastening element can come in contact with the skin or any garments of the wearer.

Finally, the new supporter is extremely simple and inexpensive, particularly as compared with similar types of garment supporters heretofore proposed which require for their production expensive machinery and a relatively large number of manufacturing steps of operations. The supporter according to the present invention can be made with comparatively simple and inexpensive machinery and very few operations.

Variations and modifications may be made within the scope of this invention, and portions of the improvements may be used without others.

Having thus described the invention what is claimed as new is:—

1. A garment supporter comprising a loop member having side arms; an eye member; a tab member; and an element having an inner end hooked to the loop member, an intermediate section looped through the eye member, and an outer end overlying the inner end, extending between the side arms and gripping the tab member to the inner end.

2. A garment supporter comprising a loop member; an eye member; an element having an inner end hooked to the loop member, an intermediate section looped through the eye member, and an outer end overlying the inner end; and

a tab member extending upwardly in back of the loop and eye members, thence downwardly and completely around the outer end of the element where it is pressed into firm engagement with the inner end of the element.

3. A garment supporter comprising a loop member; an eye member; an element having an inner end hooked to the loop member, an intermediate section looped through the eye member, and an outer end overlying the inner end and having prongs thereon; and a tab member extending upwardly in back of the loop and eye members, thence downwardly and hooked around the outer end of the element so that the prongs bite into the same, and thence between the outer and inner ends of the element where the tab member is held in firm engagement by said ends.

4. A garment supporter comprising a loop member having side arms; an eye member; an element having an inner end hooked to the loop member, an intermediate section looped through the eye member and an outer end overlying the inner end and extending between the side arms; and a tab member extending upwardly in back of the loop and eye members, thence downwardly and completely around the outer end of the element where it is pressed into firm engagement with the inner end of the element.

5. A garment supporter comprising a loop member; an eye member; an element having an inner end hooked to the loop member, an intermediate section looped through the eye member, and an outer end overlying the inner end; a tab member; and means at one end of the tab member for strengthening the same, said tab member extending upwardly in back of the loop and eye members, thence downwardly and completely around the outer end of the element, so that the edge thereof bites into the strengthening means on the tab member, and thence between the outer and inner ends of the element where the tab member is held in firm engagement by said ends.

6. A garment supporter comprising a loop member; an eye member; a tab member having a coating of cellulose material at one end thereof; and an element having an inner end hooked to the loop member, an intermediate section looped through the eye member, and an outer end overlying the inner end and gripping the coated end of said tab member to the inner end.

7. A garment supporter comprising a loop member; an eye member; a tab; a button on the tab; and an element looped about the eye member and the loop member, and having an outer section extending from one to the other of the latter members to grip the tab to the element at the lower end thereof and to enable the tab to be extended completely around the element and to bring the button into gripping register with the loop member.

8. A garment supporter comprising a loop member having side arms and a crossbar; an eye member; an element looped through the eye member and having an inner section secured to the loop member, and an outer section extending around the crossbar and between the side arms; and a tab member having one end interposed between and secured to the crossbar and the outer section of said element, and the other end thereof extending backwardly about the end of the outer section of the element and looped about the element so as to enclose the same completely.

9. A garment supporter comprising a loop member having side arms and a crossbar; an eye member; an element having an inner section

hooked around and secured to the crossbar, an intermediate section looped through the eye member, and an outer section overlying and extending around the inner section and between the 5 side arms of the loop member; prongs at the free end of the outer section; and a tab member having one part thereof impregnated with a strengthening medium and one end interposed

and firmly gripped between the inner and outer sections of the element, and the other end thereof extending backwardly about the end of the outer section of the element so that the prongs engage with the impregnated part of the tab member, 5 and thence looped about the element so as to enclose the same completely.

LOUIS SAMETZ.
